NICOTINE SEPARATING COOL SMOKE PIPE
STEM

Jacob Machemer, Jackson Heights, N. Y.

Application September 11, 1936, Serial No. 100,258

2 Claims. (Cl. 131—12)

This invention relates to new and useful improvements in a nicotine separating cool smoke pipe stem.

The invention has for an object the construction of a pipe stem which is characterized by a liquid collecting passage extending from its inner end to an intermediate point and there joining with a vent passage terminating in the top side of the pipe stem, said vent passage being associated with a smoke passage extending from the near end of the stem to its outer end and located above the liquid collecting passage. When the pipe stem is thus constructed it is possible to draw smoke through the smoke passage without being annoyed with the simultaneous passage of the juices from the tobacco. Furthermore, it is possible to draw in air which mixes with the smoke so as to cool the smoke.

Still further the invention embodies an arrangement in which one's finger may control the amount of air passing through the vent opening and so control the temperature of the smoke drawn through the smoking passage.

A further object of the invention resides in the provision of a means for closing the vent to various degrees and so eliminate the necessity of manually holding the vent closed with one's finger.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a pipe with a stem constructed according to this invention.

Fig. 2 is a transverse sectional view taken on the line 3—3 of Fig. 4.

Fig. 3 is a plan view of the pipe shown in Fig. 1.

Fig. 4 is a sectional view taken on the line 4—4 of Fig. 3.

The smoke pipe stem, according to this invention, comprises material in the form of a stem 10 having a mouthpiece portion 10^a at its outer end, and a reduced portion 10^b at its inner end for engaging into an opening in a pipe bowl such as the bowl 11. The pipe stem 10 has a liquid collecting passage 12 extending from its inner end to an intermediate point 12' and there joining with a vent passage 13 terminating in the top side of the pipe stem. The pipe stem also has a smoke passage 14 extending from its inner end to its outer end and located above said liquid collecting pas-

sage and extending through said vent passage 13.

The operation of the device is as follows:—

The pipe is supported in one's mouth by engaging the mouthpiece between one's teeth. When the smoker draws in, the smoke from the tobacco will pass through the passage 14 into the smoker's mouth. If there is any juice, some of the juices from the tobacco will collect in the bottom of the bowl and pass directly into the liquid collecting passage 12. Other of the juices will pass through the inner end portion of the smoke passage 14 until they reach the vent passage 13 and then will move down the vent passage and collect in the liquid collecting passage 12. Air from the exterior will enter the vent passage 13 and temper the temperature of the smoke.

The smoker may control the amount of air entering the passage 13 merely by holding a finger completely or partially over the outer end of the vent opening, when the light in the pipe bowl is low, to start burning the tobacco.

The pipe is provided with an arrangement for mechanically controlling the air passing through the vent passage 13. The arrangement comprises a shutter element 16 slidably mounted in a passage 17 formed in the pipe stem. The shutter 16 connects with a stem 16^a which passes through a fixedly mounted bearing disc 18 mounted in the passage 17. A collar 19 is fixed on the stem 16^a. A spring 20 is arranged coaxially on the stem 16^a and acts between the collar 19 and the disc 18 for normally urging the stem 16^a into an extended position. The extremity of the stem 16^a, indicated by the numeral 16^{aa}, extends from the inner shoulder of the stem 10, which shoulder is produced by the reduced portion 10^b, and extends into a cam shaped recess 21 formed in the adjacent shoulder of the pipe bowl. Normally, the parts are in the position shown in the figures of the drawing. The passage 13 is then unrestricted.

If it is desired to partially close the passage 13 it is merely necessary to slightly turn the bowl of the pipe relative to the stem. The cam shaped recess 21 will then press in the stem 16^a against the extending action of the spring 20 and the shutter 16 will extend partially or completely across the vent passage 13, depending merely upon the relative position of the cam recess 21 and the extended end 16^{aa} of the stem.

It is to be understood that the stem may be moulded, hand curved and the holes drilled, or made in any other suitable manner with one or more pieces of suitable material.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A nicotine separating cool smoke pipe stem, comprising material in the form of a pipe stem and having a mouthpiece portion at its outer end and a reduced portion at its inner end for engaging into an opening in a pipe bowl, said pipe stem having a liquid collecting passage extending from its inner end to an intermediate point of said stem and there joining with a vent passage terminating in the top side of said pipe stem, said pipe stem also having a smoke passage extending from its inner end to its outer end and located above said liquid collecting passage and extending through said vent passage, and mechanical means for partially or completely closing said vent passage, comprising a shutter element in a passage transversely across the vent passage, a stem connected with the shutter element and having an extended end engaging a cam recess in a pipe bowl for said stem, a pipe bowl for said stem having said recess, and resilient means urging said stem against said cam recess.

2. A nicotine separating cool smoke pipe stem,

comprising material in the form of a pipe stem having one of its ends reduced forming a shoulder portion, said pipe stem having a liquid collecting passage extending from its inner end to an intermediate point of said stem and there joining with a vent passage in the top side of said pipe stem, said pipe stem also having a smoke passage extending from its inner end to its outer end and located above said liquid passage and extending through said vent passage, a pipe bowl for said stem having an opening engaging said reduced end and a cam recess formed in the face of said pipe bowl abutting said shoulder portion, a shutter element slidably mounted in a passage formed transversely across the vent passage, a stem formed on said shutter element and having an extended end engaging said cam recess, a bearing disc fixedly mounted in the passage housing said stem and having an opening through which said stem passes, a collar formed on said stem on the side of said disc opposite said shutter element, and a spring on said stem operating between said disc and said collar to normally urge the extended end of said stem against said cam recesses, whereby said pipe bowl may be turned slightly with relation to said stem to cause said extended end to be forced inward against the normal action of said spring to force said shutter element across the vent passage to partially or entirely close said vent passage.

JACOB MACHEMER.
